UNITED STATES PATENT OFFICE

JESSE C. MARTIN, JR., OF SAN FRANCISCO, CALIFORNIA

PLUG VALVE

Application filed June 16, 1926. Serial No. 116,262.

This invention relates in general to valves and, more particularly, to improved means for operating valves.

While in the particular embodiment of the invention illustrated, the valve is of the well known rotary plug type, it will be understood that the operating mechanism disclosed is susceptible of sufficient modification, within the terms of the invention, for adaptation to other forms of valves.

The principal objects and advantages which characterize the present invention reside in the provision of an improved valve and valve operating means therefor; the provision of an improved rotary valve and improved valve operating means therefor; the provision in a valve of an improved construction of the valve proper and, more particularly, an improved construction of valve operating means, preferably for detachable association therewith; the provision of an improved valve operating mechanism which is in the nature of a complete unit capable of application to various forms of valves or in use for embodiment in the valve when the same is manufactured.

This invention is further characterized by the provision of an improved valve operating unit which serves to afford a compact power transmission means which permits of large valves being operated by hand where a relatively small amount of space is available and wherein the application of an ordinary lever to the valve stem is thus prohibited; the provision of an improved valve operating means which affords a relatively fine degree of adjustment of a valve opening by multiplication of the travel of the valve operating mechanism; the provision of a self-contained and compact valve operating unit which will serve to form a part of the valve when manufactured or which may be applied to valves already in use and which also will serve as a gland member for retaining the valve stem packing in place.

The foregoing objects and advantages, and such other advantages as may appear or be pointed out as this description proceeds, are attained by the several structural embodied

ments of this invention illustrated in the drawings, in which:

Figure 1 is a vertical sectional view of a valve constructed in accordance with this invention;

Figure 2 is a view similar to Figure 1 taken on a plane at right angles thereto;

Figure 3 is a transverse sectional view taken on the line 3-3 of Figure 1, looking in the direction indicated by the arrows;

Figure 4 is a vertical sectional view of an alternative form of the invention;

Figure 5 is a top plan view of the same;

Figures 6 and 7 are transverse sectional views taken on the lines 6-6 and 7-7 of Figure 4, respectively, looking in the direction indicated by the arrows;

Figure 8 is a plan view of a modified form of the valve structure;

Figure 9 is a vertical sectional view of Figure 8.

Referring now more particularly to the drawings, and first to Figures 1-3 inclusive, there is provided a valve body 10 having a transverse fluid passageway 11, said passageway being formed by the extensions 12, 12 and suitably secured to pipes lines (not shown) by the provision of annular valves 13, 13.

The body 10 is provided with a centrally substantially tapering bore seat 14 and a strong pocket 15, the lower end of the body, as viewed in Figures 1 and 2, being provided with an annular valve 16 to which is secured a cover plate 17 by the provision of bolts 18, 18 having nuts 19, 19.

The valve member is in the form of a tapering plug 20 and is inserted into the body 10 when the cover member 17 is removed, said valve member engaging the seat 14 and having a transverse passageway 21 adapted to register with the fluid passageway 11 for controlling the flow of fluid through. The valve member 20 is maintained snugly on its seat by the provision of a helical spring 22 engaging an axial stud 23 on the bottom of the valve member 20 and also engaging a button 24 which seats on the member 17.

The upper end of the body 10 is open, and the adjacent portion of the valve member 20 is reduced in diameter as at 25 where it passes

through the open end of said body, the valve member being further reduced, beyond the extension 25, to afford a squared valve stem 26, the latter having an axial substantially cylindrical recess 27 communicating with the 5 end of the stem.

The body 10 is provided, adjacent to the open upper ends thereof, with an annular shoulder 28, and an annular packing element 10 29 is received on said shoulder and extends over against the reduced portion 25 and hence onto an annular shoulder 30 formed by thus reducing the diameter of the valve member.

The packing may be of any suitable material, metallic, or of asbestos or the like, so 15 that it will afford a fluid-tight joint at the upper reduced end of the valve member.

For imparting rotation to the valve member I provide a power unit which includes a 20 substantially closed casing 31 containing a planetary gearing generally designated 32.

The casing 31 includes a substantially cylindrical wall reduced in diameter to afford an annular flange 33 which fits between the 25 extension 25 and the body 10 adjacent to the packing 28 and thus forms a gland for engagement with said packing.

The outer end of the casing 31 is closed by a removable plate 34, said plate being 30 secured in proper relation on the casing 31 by the provision of bolts 35, 35 having nuts 36, 36.

The plate 34 is provided with an axial opening 37 in which is journaled an operating 35 shaft 38, and having a hand wheel 39 fixedly secured thereto.

The shaft 38 projects into the casing 31 and carries a pinion 40, the latter being conveniently formed integrally with the shaft 38 40 and having a reduced axial extension 41 which is received in the recess 27 in the valve stem 26.

The pinion 40 forms a sun-gear about 45 which the planet gears 42—42 are rotatable, said gears 42 being revolvably mounted on shafts 43, 43 fixedly secured in a spider 44, the latter having a squared opening 45 for reception of the squared valve stem 26. The spider 44 is preferably formed with radial 50 guide members 46, 46 which serve to engage the inner surface 47 of the casing 31 and thus prevent rattling and other vibration of the spider and at the same time to reinforce this structure. As will be seen in Figure 3, the 55 spider is conveniently enlarged as at 48, 48, to accommodate the shafts 43, 43.

To complete the planetary gearing, the inner surface of the casing 31 is milled or otherwise formed to provide an internal ring 60 gear 49 with which the planet gears 42, 42 mesh.

In order to securely removably mount the valve operating mechanism as a unit on the valve, the casing 31 is provided with lugs 50, 65 50 through which bolts 51, 51 pass, said bolts

extending down alongside the casing and engaging in openings in the flange 52 formed on the body 10. It will be observed that by turning down the nuts on the bolts 51, the casing 31 may be caused to act as a packing 70 gland by virtue of its extending flange 33.

There is allowed sufficient clearance between the bearing member 41 and the recess 27 in longitudinal diameter to permit the pinion 40 to normally rest upon the upper 75 end of the valve stem so that said pinion will be supported in operation. However, under some conditions, it is desirable to force the valve 20 off its seat against the tension of the spring 23, an example of this being where it 80 is desired to introduce lubricant between the valve and its seat, the relatively slidable connection of the valve stem 26 and member permitting of such displacement of the valve member. Reference may be had to my co-pending application, Serial No. 88,737, for an example of a plug valve and it will be obvious that the valve member 20 may be provided with passageways, as shown in said 85 application.

Referring now to the form of the invention shown in Figures 4-7, both inclusive, it will be observed that the valve structure is substantially the same as that in Figures 1-3, and it will, therefore, be unnecessary to describe the valve structure per se in detail.

The valve shown in Figure 4, of course, includes a valve body 10^a and valve plug 20^a, the valve plug being tapering and adapted to engage a tapering seat in the body 10^a.

The body 10^a is provided with an upstanding portion 53 forming a shoulder 54 for receiving a packing 55, and the casing 56 of valve operating mechanism generally designated 57 acts on the packing 55 similarly to the arrangement shown in Figures 1-3.

The valve member 20^a is provided with a squared extension 58 which is received in a complementary opening 59 in the spider 60. The spider 60 is revolvably mounted in the casing 56 and is provided with shafts 61, 61 which carry the planet gears 62, 62, said gears being meshed with a sun-gear 63 carried by the operating shaft 64, said shaft having a reduced portion 65 journaled in an axial opening in the spider 60. The planet gears 62 also mesh with an internal ring gear 66 formed on the internal surface of the casing 56.

A cover member 67 is threaded as at 68 onto the casing 56 and serves thus to close the same against the entrance of dust and moisture. The shaft 64 passes through the cover 67 and receives a hand-wheel 69 formed with radial arms 70 for manipulating the 125 valve.

The spider 60 is provided with radial extensions 60^a, 60^a, similar to the extensions 46 shown in Figure 3 and performing a like function.

For bringing the casing 56 into impinging engagement with the packing 55, said casing, near the inner end, is provided with oppositely disposed lug portions 71, 71, adapted to receive bolts 72, 72 which engage in the body 5 10^a, nuts 73, 73, on said bolts 72 serving to force the casing down upon the packing 55. The cover member 67 is provided with a series of projections 74 for facilitating removal of 10 15 the enclosure by application of a wrench.

Upon reference to Figures 8 and 9 it will be observed that an extra heavy construction of valve member and valve body is afforded for use in high pressures, this form of invention including valve body 10^b, valve plug 20^b, said body having an upstanding annular flange 75 for forming a packing retaining portion, the packing 76 being engaged by an annular flange 77 formed on a gland 20 25 member 78. The gland member is provided with an opening 79 for accommodating the valve stem 80, the latter being squared as at 81 to facilitate its rotation. The plate 78 is provided with openings for receiving bolts 25 29, having nuts (not shown) said bolts serving to retain the plate with its flange 77 impinging upon the packing 76. The valve shown in Figures 8 and 9 is provided with limit stop means which conveniently include 30 an arcuate recess 82 cut in the stem 80 and an abutment 83, formed with the plate 78 and lying in said recess. By suitable modification, the valve operating mechanism shown in Figures 1-7 may be incorporated 30 35 in the valves shown in Figures 8 and 9.

From the foregoing description it will be observed that in the forms of the invention shown in Figures 1-7, a compact valve operating mechanism is afforded which may be 40 applied to valves or similar devices and which will afford increased power, enabling many valves to be readily manually operated and also permitting of a relatively fine degree of adjustment of the valve member.

Having thus described my invention and illustrated its use, what I claim as new and desire to secure by Letters Patent is:

1. In an operating unit for valves and the like in combination with the valve body and 50 valve stem projecting therefrom, a casing having detachable connection with said body and containing and forming a part of valve operating means engaging said stem, a packing for said stem, said casing engaging said 55 packing and serving as a gland therefor.

2. In an operating unit for valves and the like in combination with the valve body and valve stem projecting therefrom, a casing having detachable connection with said body 60 and containing and forming a part of valve operating means engaging said stem, a packing for said stem, said casing engaging said packing and serving as a gland therefor, and means for fixedly maintaining said casing in 65 impinging relation to said packing.

3. In a valve, a body, a valve member movable therein, and means for moving said valve including a gearing and casing therefor connectible as a unit to said body and valve, a part of said casing forming one of the elements of said gearing and serving to retain a packing for said valve. 70

4. An operating unit for valves including a valve body, and a valve member having a stem extending therefrom, a packing for said valve member, a gearing and a manually operable element for said valve, a casing mounted on said body enclosing said gearing and forming a part thereof, and said casing having a portion thereof serving as a gland for compressing said packing to lift said valve off its seat. 75

5. An operating unit for valves including a valve body, and a valve member having a stem extending therefrom, a packing for said valve member, gearing and a manually operable element for said valve, a casing mounted on said body enclosing said gearing and forming a part thereof, said casing serving as a removable closure for one end of said valve body and having an extending portion serving as a gland for compressing said packing to lift said valve off its seat. 85 90

6. An operating unit for valves including a valve body, and a valve member movable to and from its seat and having a stem extending therefrom, a packing for said valve member, gearing and a manually operable element for said valve having a slidable connection thereto, a casing mounted on said body enclosing said gearing and forming a part thereof, said casing serving as a removable closure for one end of said valve body removable with the gearing as a unit therefrom and having an extending portion serving as a gland for compressing said packing to move said valve relative to its seat. 100 105

7. An operating unit for valves including a valve body, and a valve member having a stem extending therefrom, a packing for said valve member, gearing and a manually operable element for said valve, a casing mounted on said body enclosing said gearing and forming a part thereof, said casing having a portion thereof serving as a gland for compressing said packing, and a removable closure for said casing whereby access may be had to said gearing without permitting leakage at said packing. 110 115

8. In a valve, a valve body open at one end and having a tapered valve seat and a tapered valve engaging said seat, resilient means tending to hold the valve on its seat, a packing for said valve member, a gear casing mounted upon and adapted to engage said packing and project into said open end to form a closure therefor, a gearing in said casing, and having a slidable connection with said valve and for imparting rotation thereto, said connection permitting independent 120 125 130

movement of the valve relative to its seat irrespective of its open or closed position.

9. In a valve, a casing open at one end and having a tapered valve seat and a tapered valve engaging said seat and having a part projecting through said open end, a packing for said valve arranged in said open end, resilient means tending to keep said valve on its seat, a gearing and a manually operable element for said valve mounted on said valve casing, and having a portion forming a fluid tight closure for said open end by engagement with said packing, said gearing having connection with said valve member for imparting rotation thereto but permitting movement of said valve to and from its seat irrespective of its open or closed position.

In testimony whereof I have hereunto signed my name.
